UNITED STATES PATENT OFFICE

HENRY L. CROWLEY, OF EAST ORANGE, NEW JERSEY, ASSIGNOR TO HENRY L. CROWLEY & CO. INC., OF EAST ORANGE, NEW JERSEY, A CORPORATION OF NEW JERSEY

INSULATOR FOR HEATERS FOR ELECTRON DISCHARGE DEVICES

Application filed December 7, 1930. Serial No. 412,333.

This invention relates in general to an insulating ceramic spacer member to be used in the heater element of electron discharge devices between the heater and the cathode.

5 One of the objects of this invention is the provision of a spacer element for such devices which permits of a decrease in the heating time required to cause full emission of electrons after initial energization of the heater.

10 Another object of this invention is the provision of a spacer element of this type which gives increased life to electron discharge devices in which it is employed.

15 A still further object of this invention is to provide a spacer element of the above type of such form as to improve the quality of output of electron discharge devices by reducing the noise, hum and the like normally 20 encountered in use of such devices.

25 A further object of this invention is the provision of a spacer of the above type which is of such form as to eliminate the microphonic noise due to the relative movement 30 between the heater and the spacer.

These and other objects as will appear from the following disclosure are secured by means of this invention.

This invention resides substantially in the 35 combination, construction, arrangement and relative location of parts, all as will be described in greater detail below.

Referring to the drawing—

Fig. 1 is a perspective view of a ceramic 40 spacer body made in accordance with the principles of this invention;

Fig. 2 is a side elevational view of this spacer.

In electron discharge devices such as vacuum tubes employed in radio circuits at the present time, especially those which are energized by alternating current use a cathode, a heater for the cathode, and an insulating body between the cathode and heater by means of which they are held in proper spaced relation. Many attempts have been made to form this insulating body in such a manner that the time required to heat up the cathode where it gives off electrons will 45 be decreased. Likewise, attempts have been

made to so construct the insulating body that it will have no deleterious effect on the life of the heater element, and will not, because of relative movement with respect thereto, produce undesired noises when the device is 55 in use. One of the reasons for the slowness in the heating up of such indirectly heated cathodes, as are now known, is the mass of the spacer element and the thickness of the walls thereof. The general purpose of this invention is to decrease the time required for 60 heating up the device, reduce the thickness of the walls of the spacer element without impairing its insulating qualities, increase the life of the device and decrease the production of undesired noises, when in use.

65 The manner in which these advantages are secured will be more readily understood by reference to the drawing. The insulating spacer body 1 is shown, for purposes of illustration, with an approximately oval or elliptical cross section having two passages 2—2 extending longitudinally therethrough from end to end. These passages are separated by a transverse wall 3. As is shown in the drawing, the thickness of all the walls is the same. By a construction of this type these walls may be made relatively thin to effect a reduction in the mass of the insulator, and a reduction in the time required for the heat to 70 travel from the heater to the cathode which surrounds the heater and fits it snugly. The heater which is usually in the form of a straight or coiled wire filament passes through the passages 2 throughout their 75 length. The insulating body has been, of course, shown in the drawing considerably enlarged, in order to clearly illustrate its construction, but it is to be understood that it is a relatively small thing in actuality. By 80 making the passages of the form shown, it is possible to make the walls of the insulator relatively thin, and of uniform thickness throughout. It is, of course, apparent that any form which accomplishes these purposes 85 falls within the spirit and scope of this invention. Another feature of these passages is illustrated by pointing out that if the heater fitted snugly in the passages the relative 90 movement between the heater and the insu- 95 100

lating body produces undesirable sounds when the device is in use. If the passages are a little larger in cross section than the heater similar undesired results are secured, but if the holes are of sufficient size with respect to the filament considerable improvement is secured. The holes in practice should be sufficiently large to leave the filament practically free, so that if relative movement does occur between the filament and the insulating body the filament will not be in contact therewith.

In practice the general width of the body as indicated by A in Fig. 1 may be 0.062". The width of the transverse wall 3 indicated at B may be 0.042". The width of the passages 2 may be, at the point indicated by C, 0.016". The thickness of the walls as indicated at D may be 0.016". These dimensions are given as examples, and not in a limiting sense. If the round holes of the insulator disclosed in the copending application of Henry L. Crowley, Serial No. 370,789, filed June 14, 1929, are say from 0.065" to 0.016", a reduction in area of 12% is secured while with the construction shown in this case a reduction in area of 37% is secured. It will be at once apparent, therefore, that by means of this construction the mass of the insulator may be materially reduced, without seriously interfering with its use for the intended purpose.

The life of the heater is increased because of the fact that a better heat distribution is effected in all directions, and the heat is more rapidly transmitted through the walls of the insulator because of their uniform thickness and relative thinness. By reason of having the heater relatively free in the passages the filament heats up faster and reaches a higher temperature and has a higher resistance so that a larger wire can be used for the same operating current. The life of the heater is increased by reason of the use of a large wire and because the damaging current surge is minimized. The filament being free in the passage is not cooled appreciably by the cold insulator and as a result its resistance rises rapidly preventing or decreasing the initial current surge.

The insulating body of this invention may be made of extruded powdered metal oxides, in accordance with the copending application of Robert M. Crowley and George B. Crowley, Serial No. 344,091, filed March 2, 1929.

I am of course well aware that some changes in the form and construction of the device may be accomplished by those skilled in the art without departing from the principles of this invention, and I do not, therefore, desire to be limited to the disclosure as given for purpose of illustration, but rather to the scope of the appended claims.

What I seek to secure by United States Letters Patent is:

1. A heater device for radio tubes compris-

ing a tubular insulating member having a pair of passages extending longitudinally therethrough forming walls of uniform thickness throughout, and a heater wire passing loosely through said passages.

2. A heater device for radio tubes comprising a tubular member of insulating material having two passages therethrough separated by a transverse wall, said transverse wall and the walls of said body being of uniform thickness, and a heater wire passing loosely through said passages.

3. A heater device for radio tubes comprising a tubular member of insulating material having a pair of semi-elliptical passages extending therethrough separated by a transverse wall, and a heater filament passing loosely through said passages.

4. A heater device for radio tubes comprising a heater filament, an insulating support and spacer member for said filament comprising a tubular ceramic body having a pair of longitudinal passages, each passage having a cross section many times greater than the cross section of the filament, and the walls of said tubular member being of substantially the same thickness.

5. A heater device for radio tubes comprising an elliptical shaped tubular insulator member having a transverse wall extending across the minor axis of the tubular element, the elliptical walls and transverse walls being of substantially the same thickness, and a heater filament loosely passing through said tubular element on opposite sides of said transverse wall.

In testimony whereof I have hereunto set my hand on this 6th day of December A. D. 1929.
